TOOL FOR FLARING OR BEADING TUBING

George M. Graham, Detroit, Mich., assignor to
 Hinckley-Myers Division of Kent-Moore Organiza-
 tion Inc., Jackson, Mich., a corporation
 of Michigan

Application November 24, 1943, Serial No. 511,513

4 Claims. (Cl. 153—79)

1

This invention relates to an improved tool for forming the end portion of a metal tube such as flaring or beading the same.

The object is to provide a small portable hand tool of the character described adapted particularly for use in repair shops and service stations.

Metal tubing such as hydraulic brake tubing and the like is usually flared at the end to assist in coupling the sections of the tubing together to complete a system. It is also frequently desirable to form a bead in the tube. In repairing such systems the length of tubing which may be necessary to make the repair varies widely and it is not convenient to stock sections having flared or beaded ends in all the lengths that may be required.

This improved tool may be held in the hand to perform any such operation. If desired the body of the tool may be gripped in a vise. The tool includes the die which receives the end of the tube to be formed and the cooperating punch which in conjunction with the die produces the proper shape upon the end of the tube. The entire assembly is a complete unit and the body of the tool is so formed that the die blocks are held securely in position and in turn securely hold the tube in position during the forming operation.

An object is to provide a compact hand tool of this character wherein the body is so constructed that the die blocks when gripped therein are accurately aligned with the punch. A meritorious feature of my construction is that the die blocks are readily replaceable with other die blocks and the body of the tool is so formed as to facilitate this replacement. The punch member is also readily replaceable.

The above objects and others will be more fully apparent from the following specification, claims and accompanying drawings wherein:

Figure 1 is a plan of a tool embodying my invention,

Figure 2 is a front elevation of the tool shown in Figure 1,

Figure 3 is a cross-sectional view taken on the line 3—3 of Figure 2,

Figure 4 is a cross-sectional view taken on the line 4—4 of Figure 2,

Figure 5 is a fragmentary broken-away sectional view showing the punch member acting upon the end of a tube during the first step of flaring operation,

Figure 6 is a fragmentary broken-away view showing the punch member acting upon the end

2

of the tube during the second step of the flaring operation,

Figure 7 is an elevation of a fragment of a modified form of my improved tool,

5 Figure 8 is a cross-sectional view taken on the line 8—8 of Figure 7,

Figure 9 is a fragmentary cross-sectional view showing a bead forming punch in operative position.

10 My improved tool comprises a body portion having bifurcations 10 and 12 terminating at one end in a portion 14 cored out to provide a guideway for a ram 16. The body is provided at the opposite end with a die-receiving channel portion 15 formed by extensions 18 and 20 of the bifurcations 10 and 12, respectively.

These end extensions are shown in cross-section in Figure 4 and are provided with oppositely disposed inwardly projecting bottom flanges

20 spaced apart by a space 22 as shown in Figure 4. End extension 20 carries a pin 24 which extends freely through an opening provided in extension 18 and is provided with a head 26 as shown in Fig. 3. The pin permits the extensions 18 and

25 20 to be yieldingly urged toward each other but prevents undue separation. The free positioning of pin 24 within the opening in extension 18 provides a certain amount of play but constitutes a positive stop against excessive spreading move-

30 ment of extension 18 with reference to extension 20. At the same time extensions 18 and 20 may be moved toward one another against the inherent spring in the branches of the bifurcation, of which 18 and 20 are simply extensions, at least 35 to the limit of play permitted by such free positioning.

These extensions 18 and 20 constitute in combination a channel portion adapted to receive complementary die blocks 30 illustrated particu-

40 larly in Figures 3 and 4. These die blocks are so shaped as to exhibit complementary semi-circular cavities 32 which when disposed in fac-

45 ing relationship provide a tube-receiving channel. Two pairs of different diameter semi-circular passageways are provided. In Figures 3 and 4, a tube 34 is shown as received between the die blocks within the channel formed by one of the two pairs of cavities.

The ram 16 is cored out at one end as at 36 50 to receive a punch member 38. The punch member has a flange 40 which positions it within the cored out cavity of the ram and the two ends of the punch member shown in Figures 1, 5 and 6 are differently formed to perform the two necessary steps in the flaring operations as herein-

after described. The punch member itself and the particular shape of the two ends is old in the art as shown in the patent to Corrigan 2,117,543.

The body is bifurcated for such a distance as to permit ready removal of the punch member from the end of the ram and replacement with a different punch member. The branch 12 of the bifurcated portion of the body is arched as shown at 13 to impart spring thereto so that the extensions 18 and 20 of the two branches 10 and 12 of the bifurcated portion of the body are relatively yieldable toward each other to grip the die blocks 30 securely therebetween.

In Figures 1 to 4, a hand clamping device is provided to grip these extensions 18 and 20 together against the die blocks. This clamping device comprises a pair of cooperating plates 41 and 42 held together by two tightening bolts 44 as shown in Figures 1 to 4 inclusive. When this clamping device is engaged about the bifurcation of the tool, the tool may be held in the hand to perform the forming operation.

If desired, the die-receiving channel portion of the tool body may be received within a vise in a manner which is well understood. Tightening of the vise thereagainst will maintain the cooperating die blocks in their proper position. The die blocks rest at one end against the pin 24 and are prevented thereby from endwise movement.

The die blocks are supported in line with the ram passageway through the portion 14 of the body. The punch member 38 is therefore supported in line with the tube receiving passageway within the die blocks.

In Figures 7 and 8 is shown a modified form of construction. In this modification, the channel portion is integral as shown in Figure 8. This channel portion is indicated at 50. Die blocks 52 are shown positioned therein. These die blocks have such a combined dimension that they project above the top surface of the channel 50. A plate 54 is pivoted by a stud 56 to an ear 58 at one side of the channel 50. This plate has a notch 60 formed on its opposite end adapted to be received over the shank of a headed stud 62 threaded into an ear on the opposite side of the channel as shown particularly in Figure 8.

When it is desired to position the die blocks within the channel 50 the plate may be swung back to the dotted line position shown in Figure 7 and suitable die blocks positioned within the channel. The plate may then be swung over these die blocks to the position shown in Figure 8 and the studs tightened to secure the die blocks firmly in place. To prevent endwise movement, a plate 64 is held by studs 67 to the end of the channel as shown in Figure 7.

When it is desired to operate the tool to flare a piece of tubing the end of the tubing is cut off square. The proper size die blocks are selected and placed within the channel of the body and the square cut end of the tubing is allowed to project about one quarter inch beyond the inner edge of the die blocks toward the punch.

If the device is to be used in a vise the channel portion is placed within the vise and just sufficient pressure placed thereon to hold the die blocks in place. If it is to be used with the hand clamp such clamp is similarly tightened against the blocks. The proper size punch member or flaring tool is then placed within that end of the ram adapted to receive the same. The ram punch is then moved toward the tubing to enter the pilot end of the punch into the tubing. The end

of the ram is then tapped with a hammer until the guide line 66 shown thereon in Figures 1, 2 and 5 is brought in line with the end of the body as shown in Figures 1 and 2. This will have adjusted the tubing to the proper position between the die blocks for carrying out the flaring operation. The hand clamp or vise is then tightened down to securely hold the die blocks against the tubing in such a manner that further endwise slippage of the tubing is prevented.

In the first step of the flaring operation the outwardly concave end of the punch shown in Figure 5 is utilized to shape the end of the tube as illustrated in such figure. In the second step 15 of the flaring operation the opposite end of the punch is employed to finish the shape of the flared end of the tube as shown in Figure 6.

On the construction shown in Figure 9 a bead forming punch is employed. The body 68 of this punch is provided with an arcuate die portion 70 which is complementary to an arcuate die portion 72 on die blocks 74. The end of the punch also is provided with a projecting male member 76 of a size to enter the end of the tube as shown.

The end of the tube being shaped seats within the bottom of the recess about the male portion 76. The tube is held against endwise slippage between the die blocks as hereinabove described in connection with the description of the flaring operation. When the impact pressure is applied to the end of the tube by the punch the tube is upset between the complementary arcuate die faces 70 and 72 of the punch and die blocks respectively forming a circumferential bead about the tube.

What I claim is:

1. In a tube shaping tool, a bifurcated body terminating at one end in a juncture of the two branches of the bifurcation in a tubular guideway for a ram and terminating at the opposite end in the free end portions of the two branches of the bifurcation, said free ends being complementary and spaced apart and shaped to define a channel therebetween in line with the tubular guideway, a ram reciprocally mounted within said tubular guideway, complementary die blocks removably received within the channel between the free ends of the two branches of the bifurcation, a pin connecting the free ends of the two branches of the bifurcation holding them against separation while permitting relative limited movement of such two branches toward and away from each other, said pin disposed at the end of the channel between said free ends constituting an end stop for the die blocks, and clamping means embracing the free ends of said branches holding the die blocks therebetween.

2. A tube shaping tool comprising, in combination, a bifurcated body, the juncture of the branches thereof being formed into a sleeve adapted to slidably receive a ram, a die block securing channel formed from opposed faces of said branches extending in line with said sleeve, one branch of said bifurcation being arched outwardly between said sleeve and said channel to impart resilience to the branch enabling the same to be resistingly swung toward the other branch to vary the distance therebetween, and a pin connecting said branches adjacent to the free ends thereof serving as a stop for limiting lateral movement of the branches away from one another, said pin extending across said channel at the outer end thereof also serving as a stop limiting endwise movement of the die blocks inserted 60 into the channel.

3. In a tube shaping tool, a bifurcated body terminating at one end in a juncture of the two branches of the bifurcation in a tubular guideway for a ram and terminating at the opposite end in two spaced apart free end portions of the two branches of the bifurcation, at least one of said branches being flexible for resisted movement toward and away from the other branch, said free end portions being complementary and shaped to define a channel therebetween in line with the tubular guideway, a ram reciprocally mounted within said tubular guideway, complementary die blocks removably received within the channel between the free end portions of the two branches of the bifurcation, and means embracing the free end portions of said branches and adapted to compress the free end portions toward one another to cause the latter to tightly clamp the die blocks therebetween.

4. In a tube shaping tool, a bifurcated body terminating at one end in a juncture of the two branches of the bifurcation in a tubular guideway for a ram and terminating at the opposite end in two spaced apart free end portions of the two branches of the bifurcation, at least one of said branches being flexible for resisted movement toward and away from the other branch,

said free end portions being complementary and shaped to define a channel therebetween in line with the tubular guideway, a ram reciprocally mounted within said tubular guideway, complementary die blocks removably received within the channel between the free end portions of the two branches of the bifurcation, and said free end portions of said branches being so constructed and arranged that they may be compressed toward one another to tightly clamp the die blocks therebetween.
